(57) **CLAIM**

The ornamental design for an anemometer assembly as shown and described.

DESCRIPTION

FIG. 1 is a front elevational view of an anemometer assembly according to my new design;
FIG. 2 is a left side elevational view of the anemometer assembly of FIG. 1;
FIG. 3 is a right side elevational view of the anemometer assembly of FIG. 1;
FIG. 4 is a rear elevational view of the anemometer assembly of FIG. 1;
FIG. 5 is a top plan view of the anemometer assembly of FIG. 1;
FIG. 6 is a bottom plan view of the anemometer assembly of FIG. 1;
FIG. 7 is a perspective view of the anemometer assembly of FIG. 1; and,
FIG. 8 is a perspective view of the anemometer assembly of FIG. 1 from an opposite side of the anemometer assembly as shown in FIG. 7.
The broken line showing in the drawings is for illustrative purposes only and forms no part of the claimed design.
